UNITED STATES PATENT OFFICE.

JOHN R. WILLIAMS, OF SCRANTON, PENNSYLVANIA.

DESIGN FOR A HORSESHOE-CALK.

SPECIFICATION forming part of Design No. 29,793, dated December 13, 1898.

Application filed November 17, 1898. Serial No. 696,734. Term of patent 14 years.

To all whom it may concern:

Be it known that I, JOHN R. WILLIAMS, a citizen of the United States, and a resident of Scranton, in the county of Lackawanna and State of Pennsylvania, have invented and produced a new and original Design for a Calk for Horseshoes, of which the following is a specification, reference being had to the accompanying drawings, forming part thereof, in which—

Figure I is a perspective view of my calk for horseshoes, showing my new design. Fig. II is a side elevation of the same. Fig. III is a vertical longitudinal section thereof on a central line. Fig. IV is a face view of the calk. Fig. V is a cross-section of the middle portion looking toward the inner end of the calk.

As shown in the drawings, the leading or material features of my design consist in an angular base, radial wings having rounded corners and ends arched from corner to corner, U-shaped grooves formed between the wings, and inclined portions from the inner ends of the grooves to the sides of the base.

Having thus described my invention, the following is what I claim as new therein and desire to secure by Letters Patent:

The design for a calk for horseshoes substantially as herein shown and described.

JOHN R. WILLIAMS.

Witnesses:

JAMES GARDNER SANDERSON,
J. N. CAPWELL.
